Primary Examiner — T Chase Nelson*Assistant Examiner* — Mary Claire Ramirez(74) *Attorney, Agent, or Firm* — Buchanan Ingersoll & Rooney PC(57) **CLAIM**

The ornamental design for a toner cartridge, as shown and described.

DESCRIPTION

FIG. 1 is a front elevational view of a toner cartridge showing our new design;

FIG. 2 is a rear elevational view thereof;

FIG. 3 is a left side elevational view thereof;

FIG. 4 is a right side elevational view thereof;

FIG. 5 is a top plan view thereof;

FIG. 6 is a bottom plan view thereof;

FIG. 7 is a front, right and top perspective view thereof;

FIG. 8 is a rear, left and bottom perspective view thereof; and,

FIG. 9 is a further perspective view thereof showing the toner cartridge in use.

The broken line portions of the toner cartridge form no part of the claimed design.

1 Claim, 9 Drawing Sheets(56)
